UNITED STATES PATENT OFFICE.

ALFRED JOHNSON, OF CHICAGO, ILLINOIS.

DESIGN FOR A SHOE OR SIMILAR ARTICLE.

54,215.

Specification for Design.

Patented Nov. 18, 1919.

Application filed August 25, 1919. Serial No. 319,829. Term of patent 14 years.

To all whom it may concern:

Be it known that I, ALFRED JOHNSON, a citizen of the United States, and residing in the city of Chicago, county of Cook, and State of Illinois, have invented a new and original ornamental Design for a Shoe or Similar Article, of which the following is the specification, reference being had to the accompanying drawings, forming a part thereof.

On the drawings:

Fig. 2 is a side elevation thereof taken from the opposite side of the shoe.

Fig. 3 is a top plan view thereof.

I claim:

The ornamental design for a shoe or similar article as shown.

ALFRED JOHNSON.
